ELECTRON DISCHARGE TUBE

Henry J. McCarthy, Danvers, Mass., assignor to
 Hygrade Sylvania Corporation, Salem, Mass.,
 a corporation of Massachusetts

Application August 6, 1936, Serial No. 94,524

4 Claims. (Cl. 250—27.5)

This invention relates to electron discharge tubes, and more particularly to tubes arranged to have their emitting members heated by a varying current.

5 An object of the invention is to provide a radio tube having a bi-part electron emitting cathode, which is designed so that the percent of "hum" in the output circuit is reduced to a minimum, when the cathode is energized by alternating current.

10 A feature of the invention relates to a tube of the indirectly heated cathode type, wherein the cathode is provided with two separated emitting members so connected to their heaters and heating circuit as to reduce the percent of "hum" in the output circuit.

15 A further feature relates to the novel organization, arrangement and relative location of parts which go to make up an improved electron discharge tube for use on alternating heating current.

20 Other features and advantages not specifically enumerated will be apparent after a consideration of the following detailed descriptions and the appended claims.

25 While the invention will be described herein as embodied in one particular type of tube, namely a triode, it will be understood that this is done merely for explanatory purposes, and that the invention can equally well be applied to so-called multi-grid tubes. Accordingly in the drawing,

30 Fig. 1 is a composite schematic structural and circuit diagram showing the invention embodied in a triode.

35 Fig. 2 is a view of a tube mount embodying features of the invention.

Fig. 3 is an enlarged detail view of one manner of assembling the bi-part cathode.

40 Referring to Fig. 1 of the drawing, the numeral 1 represents any well-known form of enclosing envelope either of glass or metal, and preferably although not necessarily, highly evacuated. It will be understood from the ensuing description that the invention can also be embodied in gas or vapor type tubes as well as in vacuum tubes. In accordance with the present invention the electron emitting cathode is formed in two separate sections indicated by the numerals 2 and 3, and associated with the two cathode sections is 45 a common grid 4 and a common anode or plate 5. In accordance with well-known processes the outer surface of each of the members 2 and 3 is provided with an electron emissive coating. For the purpose of raising the coatings to emissive 50 temperature, each cathode section is provided

with a filament or heater wire 6, 7, and while the drawing shows the heater wires in the form of a simple V or hairpin shape, it will be understood that this showing is purely schematic and if desired each heater may take the form of a plural folded wire carrying a coating of refractory insulation. As an example of such a heater reference may be had to co-pending application Serial No. 620,157. In any event whichever type of heater wire is employed it should be supported 10 within the associated cathode member, so that the wire proper is out of electrical conductive contact with the cathode member.

15 As shown in the drawing the cathode members and the heater wires are preferably alike in construction and the right-hand opposing ends of the wires are directly connected by means of a metal strap 8, while the other opposing ends of the wires are connected by conductors 9 and 10 to the terminals of the secondary winding 11 of 20 the usual filament heating transformer. Preferably the electrical midpoint of this secondary winding is connected to ground as shown. Each of the cathode members 2, 3, is also connected by its respective metal jumper 12, 13 to the conductors 9 and 10. While the tube may be used in any well-known circuit, merely for purposes of explanation it will be assumed that the tube is to be used as an amplifier of low frequency signals in which event the grid 4 will constitute 25 the control grid and the signal input circuit represented schematically by a coupling transformer is connected as shown. Thus the secondary winding 12a of the input transformer has one terminal connected to the control grid 4 and the other end 30 connected to ground, it being understood that, if desired, any of the well-known grid biasing arrangements may be employed so as to insure that the tube works on the proper part of its characteristic curve. Likewise the output circuit for the 35 tube may be of any well-known character, and merely for purposes of explanation it is shown as including the primary winding 13a of an output transformer and a source of plate or anode potential 14. It will be understood that the details of 40 the input and output circuit such as by-pass condensers, choke coils, and the like have been omitted from the drawing for the sake of clarity and inasmuch as these elements are well-known in the amplifier art. It will also be understood 45 that instead of transformer couplings for the input and output circuit any other well-known form of coupling such as resistance, or choke coupling may be employed.

50 I have found that with the foregoing described 55

arrangement it is possible to heat the filaments 6 and 7 from a source of low frequency alternating current such for example as that usually supplied by alternating current mains, without the production of appreciable hum in the output circuit. This probably results from the fact that the bi-part cathode has both sections arranged symmetrically with respect to the common grid and the common plate, and also from the fact that the sections of the cathode are connected in "balanced" relation to the alternating current heating circuit, so that the "hum" components of the heating current in the plate or output circuit, are balanced out. Furthermore this arrangement simplifies the structure of the tube as a whole while achieving the hum elimination, since it is not necessary to bring out separately the leads from the cathode sections and all that is necessary is to bring out the two leads represented by the conductors 9, 10, and the grid and plate leads.

While the invention may be embodied in a wide variety of tube structures, there is shown in Fig. 2 one possible arrangement of the various electrodes in the form of a radio tube mount, although it will be understood that the showing of Fig. 2 is merely illustrative. In this figure the parts corresponding to similar parts of Fig. 1 are designated by the same numerals. Thus the mount shown comprises a press or other conventional standard or header 15 into which are sealed, or upon which are insulatingly supported, the various lead-in and support wires 16 to 21 inclusive. The wires 16 and 21 support the tubular plate or anode 5; the wire 17 supports the usual wire-wound grid 4; while the wires 18 and 20 are connected to the terminals of the heater wire 7. The wires 18 and 20 are likewise connected to the terminals of the heater wire 6. The cathode is formed in two separate sections each comprising a tubular metal sleeve 22, 23 mounted in longitudinal spaced relation as for example by an insulating bead or bushing 24, and the outer face of each sleeve being provided with the usual electron emissive coatings 25, 26. Each heater wire is directly connected by a jumper 12, 13 to its associated cathode sleeve. While the drawing shows the heater wires 6 and 7 freely supported within their respective sleeves, it will be understood that any well-known manner of insulatingly spacing the wires from their respective sleeves may be employed, such for example as illustrated in application Serial No. 620,157. If desired, the various electrodes of the mount may be held in fixed spaced relation by the usual upper and insulator spacer members in the form of mica discs 27, 28. It will be seen therefore

that with this arrangement it is possible to connect the heater filaments directly to their associated cathode sleeves within the tube, and it is necessary to bring out only four wires as shown in Fig. 2, and yet the tube may be used with alternating heating current without the introduction of undesirable hum in the output circuit. 5

While Fig. 2 shows one possible structure for carrying out the invention, it will be obvious to those skilled in the art that various changes and 10 modifications may be made therein without departing from the spirit and scope of the invention.

What I claim is:

1. An electron discharge tube having a bi-part 15 cathode assembly comprising a pair of separate emitting members, a heater wire for each member and insulatingly spaced therefrom, a direct connection from an end of one heater wire to its associated emitting member, a direct connection 20 from an end of the other heater wire to its associated emitting member, the other ends of said heater wires being connected together, and a single anode common to both parts of said cathode. 25

2. An electron discharge tube of the alternating current heater type, the combination of a pair of cathode sleeves, a heater wire inside each sleeve, means connecting the heater wires in series, a metallic strap directly connecting one end 30 of the serially connected heater wires to one cathode sleeve, and a separate metallic strap directly connecting the other end of the serially connected heater wires to the other cathode sleeve, and a single anode common to both parts 35 of said cathode.

3. An electron discharge tube of the alternating current heater type, the combination of a bi-part cathode, a grid for each part of the cathode, 40 an anode common to both parts of the cathode, each part of said cathode comprising a cathode sleeve and a heater filament, the heater filaments being connected in series with the outer ends directly connected to the cathode sleeves. 45

4. An electron discharge tube of the alternating current heater type, the combination of a pair of indirectly heated cathodes each including a cathode sleeve and a heater wire, a grid for each of the sleeves, an anode common to both sleeves, a pair of lead-in wires for connection to a source 50 of heating current, a direct connection from one of the lead-in wires to one of the sleeves, a direct connection from the other of the lead-in wires to the other sleeve, said heater wires being connected in series across said lead-in wires. 55
